UNITED STATES PATENT OFFICE.

LEWIS JULIUS HEWES, OF OAK PARK, ILLINOIS, ASSIGNOR TO TRAYLOR ENGINEERING & MFG. CO., OF ALLENTOWN, PENNSYLVANIA, A CORPORATION OF DELAWARE.

CRUSHER.

1,329,835.

Specification of Letters Patent.

Patented Feb. 3, 1920.

Application filed June 18, 1919. Serial No. 305,150.

To all whom it may concern:

Be it known that I, LEWIS J. HEWES, a citizen of the United States, resident of Oak Park, Illinois, have invented certain new and useful Improvements in Crushers, of which the following is a specification.

My present invention relates to improvements in crushers and more especially those of the gyratory type in which the crusher shaft is supported from the top of the crusher frame.

The invention aims to provide a rigid support for the upper end of the shaft which can be easily and quickly removed, which will offer a minimum amount of obstruction to the feeding to the crusher of the material to be operated upon, and eliminate the necessity for a hopper which will enable the concaves to be removed, and replaced without requiring removal of the shaft support, and which will not have any tendency of the center bearing to rock.

With these and other objects in view the invention includes the novel features of construction and arrangement and combination of parts hereinafter described and particularly defined by the appended claims.

An embodiment of my invention is illustrated in the accompanying drawings, in which, Figure 1 is a transverse sectional view.

Fig. 2 is a partial section on a line at a slight angle to Fig. 1.

Fig. 3 is an enlarged partial plan view.

Referring by reference characters to this drawing the numeral 1 designates the annular frame member provided with the crushing concaves 2 and 3, the gyratory shaft carrying the crushing cone 4, which parts, except as hereinafter specified, may be of the ordinary or any desired construction.

The frame member 1 is provided with an upwardly and outwardly flared or inclined rim 1^a, which serves to deflect the material to be crushed into the space between the cone and concaves. At diametrically opposite points this rim is provided with upwardly extending side and end walls 1^b and 1^c respectively, the said walls being flared upwardly to form tapered seats to receive the correspondingly shaped ends 5^a of the cross bar 5, which is provided intermediate of its ends with the shaft supporting hub 5^b

in which the shaft may be secured in any 55 desired manner.

The ends of the arms are machined to fixed dimensions so that any cross bar will fit any crusher frame of the particular size, and insure interchangeability, and in order 60 to provide a perfect fit and prevent any possibility of the bar ends moving in their seats, I provide the seats with bearing surfaces of a softer metal 6, preferably zinc which is anchored to the frame so as not to 65 be ruptured when the bar is removed.

In order to obtain the proper fit and prevent any movement or creeping of the bar ends in the seats a certain amount of draft is allowed on the taper sides which is obtained by blocking the bar ends a certain distance above its home position and then pouring molten zinc into the space between the ends of the bar and the walls of the seat. The bar is then removed, the blocks 70 taken out and when the bar is replaced it will have the proper draft allowance due to the taper construction. This draft is applied vertically to the bar ends by means of bolts 7 passing downwardly through the 75 bar ends and through the frame.

In order to locate the bearing in proper position relative to the frame the bar is provided with downwardly extending arc-shaped lugs or shoulders 5^b which are 80 machined to fit the inside edges of the bottoms of the bearing recesses, which fit, being cylindrical, is not affected by the draft allowance hereinbefore referred to.

In order to effect the removal of the bar 90 when desired I provide slots 1^x in the outer walls of the bearing recesses through which wedges may be driven beneath the bar ends to force them out of their seats. The bars of the largest crushers are removed by means 95 of jack screws or hydraulic jacks applied from below for which arrangements are provided.

It will be noticed that the bearing recesses or pockets are extended above the fulcrum 100 point of the shaft, which overcomes any tendency for the bearing bar to rock, the stresses being taken care of in straight lines.

It will be further noted that the bar pockets are as close as possible to each other, 105 the bar being comparatively short resulting in the most rigid construction. The pocket walls are so shaped as to offer the least ob-

struction to the feeding of rock to the crusher and at the same time provide a secure support for the bar.

Having thus described my invention what 5 I claim is:

1. In a gyratory crusher of the class described the combination with the crusher wall or frame and gyratory shaft, of a supporting member for the crusher shaft comprising a bar having a hub in the center from which the shaft is suspended, and tapered end portions fitting in tapered seats carried by said frame.
2. In a crusher of the class described the combination with a crusher wall or frame, of a supporting member for the crusher shaft comprising a bar having a hub in the center, a gyratory shaft having its upper end suspended from said hub, and tapered end portions fitting in tapered seats carried by said frame, said bar having its under surface convex in cross section between the hub and ends permitting free feed of material.
3. In a crusher, an annular crusher frame having an upwardly and outwardly flared rim and having diametrically arranged upstanding flanges having upwardly inclined walls forming tapered seats, said seats being open on their inner sides, and a shaft supporting bar having tapered end walls fitting said tapered seats.
4. In a crusher, an annular crusher frame member, raised portions on diametrically opposite sides having upwardly inclined

walls providing tapered seats open at their 35 inner sides, a shaft supporting bar having wedge shaped end portions coöoperating with said seats and arc-shaped walls on the lower side of said bar coöperating with the inner wall of the frame member and a gyratory 40 shaft suspended from said bar.

5. In a crusher, an annular crusher frame member, and a shaft supporting bar having a central shaft bearing, said frame member having diametrically arranged tapered seats, 45 and said bar wedge-shaped ends fitting said seats, said seats projecting above the lower portion of the shaft bearing and a gyratory shaft suspended from said bearing.

6. In a crusher, an annular crusher frame 50 member having vertically flaring seats, the walls of said seats being faced with a softer metal, a shaft supporting bar having wedge-shaped ends coacting with said seats, and means acting vertically on said ends for 55 forcing them into the seats.

7. In a gyratory crusher, an annular crusher frame member having vertically flaring seats, a shaft supporting bar having wedge-shaped ends coöoperating with said 60 seats, a gyratory shaft suspended from said bar, vertically acting means for forcing the said ends into the seats, the walls or bottoms of said seats having openings for the admission of means to effect removal of the 65 ends of the bar.

In testimony whereof I affix my signature.
LEWIS JULIUS HEWES.
